ROBERT SHARP, OF TUCKAHOE, NEW YORK.

TIE-ROD-WITHDRAWING JACK.

1,298,105.

Specification of Letters Patent. Patented Mar. 25, 1919.

Application filed December 4, 1918. Serial No. 265,292.

To all whom it may concern:

Be it known that I, ROBERT SHARP, a citizen of the United States, and resident of Tuckahoe, in the county of Westchester and 5 State of New York, have invented certain new and useful Improvements in Tie-Rod-Withdrawing Jacks, of which the following is a specification.

The invention relates in general to an improvement in the method of forming concrete constructions in those situations where the mold boards of the form are tied together by metal rods embedded in the concrete and which usually remain in position 15 at least until the concrete has set.

The primary object of the invention is to provide a concrete mold construction, and particularly a tie rod therefor, all the parts of which mold construction may be used 20 repeatedly without the necessity of reforming the parts, and incidental to this primary object it is desirable to provide in such a construction, a tie rod for the concrete which will permit the form boards to be removed earlier than these boards can be removed under present practices.

Broadly the invention contemplates a form of tie rod which will not only act to tie the boards together during the pouring 30 and initial stages of the setting operation but which will also tie together the outer portions where the setting process has farthest advanced. With this form of concrete tying rod it is possible, as soon as these 35 outer shells of concrete have a rigidity sufficient to hold the configuration of the structure to remove the boards so that they may be used in another location.

It has been suggested that tie rods for 40 the molds be made smooth and when the concrete has set sufficiently to permit the removal of the form to withdraw the rods by means of a turn-buckle arrangement one threaded portion of which bears on the outer 45 wall of the mold and another similar portion engages a crimped portion of the smooth rod.

In the improved method, herein disclosed, however, it is necessary to allow the rods to 50 remain in the concrete after the premature removal of the boards and especially where the rods are allowed to remain for any material time the concrete adheres to the rod to such an extent that the adoption of the

suggested use of a turn-buckle to pull the 55 rods loose is impossible and impractical.

Accordingly, the invention features a powerful rod withdrawing device capable of loosening the adhesion between the rod and concrete and designed to withdraw the 60 rod rapidly and without bending after it has been loosened from its original position in the concrete.

With the concrete exposed any attempt to pull the tie rod longitudinally out of position would result in the rod bringing with it some of the concrete. This is avoided by first giving the rod a slightly rotary movement about its own axis so that the initial withdrawing movement is somewhat in the 70 nature of a screw action. When loosened the rod may be withdrawn longitudinally without any material damage to the concrete.

In such operations there is grave danger 75 of bending the rods and especially where the rods are screw-threaded, any such bending would minimize the possibility of immediately reusing the rods in another part of the structure. 80

Accordingly, another object of the invention is to provide a guiding means for engaging as much of the tie rod as possible, taking into consideration the commercial necessity of making the device of the least 85 practical length so as to apportion the portable weight of material into a minimum number of massive parts rather than feature a long screwing device.

Various other objects and advantages of 90 the invention will be in part obvious from an inspection of the accompanying drawings and in part will be more fully set forth in the following particular description of 95 one form of mechanism embodying my invention, and the invention also consists in certain new and novel features of construction and combination of parts hereinafter set forth and claimed. 100

In the accompanying drawings:—
Figure 1 is a view in vertical section transversely of a concrete wall with the form boards in position, tied together by means of a tie rod constituting a part of a preferred form of my invention; 105

Fig. 2 is a perspective view of the wall shown in Fig. 1 with the mold boards removed and showing the parts of a preferred

form of my invention in operative engagement with one of the rods to withdraw the same; and

5 Fig. 3 is a view in side elevation of the jack constituting a part of the withdrawing means shown in Fig. 2.

In the following description and in the 10 claims, parts will be identified by specific names for convenience of expression but they 15 are intended to be as generic in their application to similar parts as the art will permit.

There is shown a wall A of concrete or 20 similar self-hardening plastic material 25 which has been poured into the form and between the boards B thereof. During the 30 pouring operation and during the initial periods of the setting operation the boards are held in position by means of tie rods 10 which extend beyond opposite faces of the 35 boards B and the boards are held in position by means of nuts C in threaded engagement with the rods 10. For this purpose the end portions of the rods are provided with screw 40 threads 11 and in one phase of the invention the threads are arranged so as to extend into the outer portions of the concrete as shown 45 in Figs. 1 and 2. These threads are arranged to form corresponding threads 12 in the outer portions of the concrete as it becomes 50 set. As is known the concrete sets progressively from the outer exposed sides inwardly toward the interior of the concrete structure and by connecting these set portions it is 55 possible to utilize the mold-board-tie-rods for the purpose of tying together the outer 60 portions of the wall A. There is therefore formed, in effect, a pair of spaced apart and tied together shells which will maintain the 65 configuration of the wall until the concrete has entirely set. By this means it is possible to remove the mold boards shortly after the 70 wall is poured. This exposes the outer sides of the wall earlier than usual and tends to 75 facilitate the rapid setting of the concrete. The rods therefore remain in the concrete longer than has been usual in prior situations 80 where it is suggested to withdraw the rods prior to or at the same time that the 85 mold boards are removed.

The mechanism for withdrawing the rods 90 features a massive construction made sufficiently light in weight so as to be handled by one man but with the metal so proportioned as to give the maximum resistance to 95 bending or distortion when in use. Featuring the simplicity of construction there is shown a screw jack 14, formed primarily of two screw parts. One of the parts is a 100 hollow casting 15 having one end enlarged to form a flange 16 for engaging the concrete over a material area thereof and which flange is held against rotary movement by the 105 frictional engagement with the concrete engaging surface 17 forming the adjacent side of

the concrete construction. This bearing element forms the female member of the screw combination and has a bore 18 of relatively large diameter provided with internal screw threads preferably of the square threaded type which have been found most effective to give the requisite strength to the threaded part of this rod withdrawing jack. The other member of the screw connection is relatively long and is provided with a bore 19 extending axially therethrough. This bore has a diameter sufficient to accommodate the rod 10 passed therethrough as shown in Fig. 2. In its most perfected construction the rod should have a sliding fit 70 in the bore so that the rod would be guided for the entire length of this member, but as these rods are usually made up of rough stock there should be sufficient clearance between the rod and shiftable member to permit a free movement of the rod but this clearance should be no more than necessary so that the member may act as a guide for engaging the greatest possible length of rod, and thus tend to prevent distortion of the 75 rod in the withdrawal of the same from the concrete.

This member is provided centrally thereof with a massive head 20 having openings 21 extending laterally therethrough to accommodate a long crow-bar 22 or similar leverage tool necessary when such devices are actuated by manual force.

Where it is desired to rotate the rod 10 slightly in the initial loosening of the same 100 from the concrete, the rod 10 is provided with an opening 23 extending therethrough and which opening is designed to be aligned with one of the openings 21 in the head thus permitting the insertion of the crow-bar 22 entirely through the head and rod. In this way the rod is pinned to the head, so as to partake of the rotary movement thereof. A shank 24 of relatively large diameter extends from one side of the head and constitutes a male member in screw threaded engagement with the bearing member and occupies substantially all of the space between the rod 10 and the bearing member. The end of the member opposite the shank is 110 reduced to form a relatively small bearing tube 25 upon which is loosely mounted a washer 26, one side of which is in bearing engagement with the head and the opposite side of which constitutes a nut engaging surface 27. A nut 28 is threaded on the rod 10 and in the actuation of the device when it is desired to move the rod longitudinally this nut is screwed up into engagement with the washer.

115 In operation and with the mold boards removed, or even with the mold boards in position, the jack is slipped on the projecting end of the rod and with the shank telescoped fully into the female member. The 120

nut 28 is then screwed onto the rod until it is in bearing engagement with the washer 26. Then by inserting the crow-bar into the opening 21 but not into the opening 23 the 5 male member may be rotated in a direction to withdraw the same out of the female member and to act through the washer and nut to withdraw the rod longitudinally out of the set concrete.

10 In those situations where it is desired to first loosen the rod by a rotary movement thereof, the nut 28 is omitted and the crow-bar passed entirely through the rod, so that with the rotation of the male member the 15 rod will be unscrewed from the threaded concrete part and when the rod is thus initially loosened the nut 28 may be screwed up into position as previously suggested and the rod rapidly withdrawn by the rotation 20 of the male member. It is preferable from a mechanical standpoint to make the shank relatively short and as it approaches the outward limit of its movement to rotate the same back into its collapsed position, then 25 rotate the nut into the advanced position to again engage the washer and the operation is continued, and if necessary repeated until the rod is fully withdrawn from the set concrete.

30 By means of a device of this character it is possible to remove the mold boards, so that on a given undertaking the amount of lumber utilized is reduced and withdrawing the rods without bending maintains the threads 35 thereon intact and permits the repeated use of the rod, without the necessity of straightening the same. The jack can be quickly installed in position and as there are but two screw parts, and these parts are necessarily 40 made quite rugged the possibility of distorting the parts through the excessive force necessary in such a situation is reduced to a minimum.

It is obvious that the jack illustrated may 45 be utilized in other locations, for instance, where it is desired to draw on a rod or cable. As one illustration of such a use, it may be noted that the jack could be mounted on a tripod and a lifting rod disposed 50 vertically in place of the rod 10 or the jack could be mounted on a suspension bridge tower to draw the cables taut.

Having thus described my invention. I claim:—

55 1. In a device of the class described, the combination with a tie rod for connecting the mold boards of a concrete form, one end of said rod which is designed to extend beyond the concrete being threaded and provided with a hole extending transversely therethrough, of a jack provided with an opening extending axially therethrough for receiving the threaded portion of the rod, said jack including a female bearing member internally screw threaded and provided

with a concrete engaging end, a male member provided with a massive head and a shank portion in threaded engagement with the bearing member, said head provided with an opening extending therethrough and 70 designed to be alined with the opening in the rod whereby a crow-bar or similar leverage tool may be inserted in said alined openings and the head and rod rotated simultaneously thereby to screw the rod out of the 75 concrete.

2. In a device of the class described, the combination with a tie rod for connecting the mold boards of a concrete form, and provided with a hole extending transversely 80 therethrough, of a jack provided with an opening extending axially therethrough for receiving a projecting portion of the rod, said jack including a female bearing member internally screw threaded and provided 85 with a concrete engaging end, a male member provided with a massive head and a shank portion in threaded engagement with the bearing member, said head provided with an opening extending therethrough and 90 designed to be alined with the opening in the rod whereby a crow-bar or similar leverage tool may be inserted in said alined openings and the head and rod rotated simultaneously thereby to loosen the adhesion be- 95 tween the rod and the concrete.

3. In a device of the class described, the combination with a tie rod for connecting the mold boards of a concrete form, one end of said rod, which is designed to extend beyond the concrete, being threaded, of a screw jack provided with a hole extending axially therethrough for receiving the threaded portion of the rod, said jack including a female bearing member internally screw 100 threaded and provided with a concrete engaging end, a male member provided with a head adapted to be engaged by a rotating tool and provided with a shank in threaded engagement in said female member and a 110 nut in threaded engagement with said rod to the outside of said male member whereby the rotation of said head in one direction will move the same into bearing engagement with the nut and act thereon to draw the rod 115 axially out of the concrete and without bending the rod, said nut adapted to be advanced on the rod.

4. In a device of the class described, the combination with a tie rod for connecting 120 the mold boards of a concrete form, one end of said rod, which is designed to extend beyond the concrete, being threaded, of a screw jack provided with a hole extending axially therethrough for receiving the 125 threaded portion of the rod, said jack including a female bearing member internally screw threaded and provided with a head adapted to be engaged by a rotating tool and provided with a shank in threaded engage- 130

ment in said female member, a nut in threaded engagement with said rod to the outside of said male member whereby the rotation of said head in one direction will move the same 5 into bearing engagement with the nut and act thereon to draw the rod axially out of the concrete and without bending the rod, said nut adapted to be advanced on the rod, and a washer loosely mounted on the male 10 member and disposed between the revoluble head and the nut threaded on the rod.

5. In a device for withdrawing a tie rod from a concrete construction, a screw jack formed of two parts, one of said parts constituting a female short bearing member with one end enlarged to form a concrete 15 engaging end designed to extend over an extensive area of the concrete and the other part constituting a male member provided 20 with a head and a shank portion threaded into said female member, said male member provided with an opening extending axially therethrough and having a diameter designed to accommodate the rod acted upon 25 and approximately to engage said rod to minimize any tendency of the rod to bend, said head provided with means for receiving a leverage tool to rotate the male member out of the female member.

30. 6. A screw jack for withdrawing tie rods from concrete constructions, including a female bearing member with one end forming a concrete engaging end and having a bore of relatively large diameter extending 35 axially therethrough, a shiftable rod guiding member provided with a bore extending axially therethrough for accommodating the tie rod for a distance substantially equal to the length of the jack when collapsed, said 40 guiding member provided centrally thereof with a head adapted to be engaged by a leverage tool to rotate the guiding member, a shank of relatively large diameter constituting a male member and fitted in said 45 large diametered bore and in screw threaded engagement with said female member, a bearing tube of relatively small external diameter extending from the side of the head opposite the shank and a washer loosely 50 mounted on said tube whereby the rod guiding member may be rotated about the rod being withdrawn, relative to both the washer and the female member while being withdrawn from the female member.

7. A screw jack for withdrawing tie rods 55 from concrete constructions including a female bearing member with one end enlarged to form a concrete engaging end and having a relatively large bore extending axially therethrough and internally screw threaded, 60 a male member having a head adapted to be engaged by a tool to rotate the member and having a shank fitted in said large bore, externally screw threaded and engaging the threads of the female member, said head and shank having a smooth bore extending axially therethrough and adapted substantially 65 to engage the rod along the entire length of the male member thereby to assist in minimizing any tendency of the rod to 70 become bent during the withdrawal thereof from the concrete.

8. A screw jack for withdrawing tie rods 75 from concrete construction, comprising two threaded parts, one part constituting a female member adapted to be held in fixed position relative to the concrete structure and the other part constituting a coacting male member threaded into said female member, said male member provided with 80 a rod receiving bore extending axially therethrough and a washer mounted loosely on said head at the end thereof opposite the end in threaded engagement in the female member, the outer end of said washer provided with a nut-engaging surface. 85

9. In a device of the class described, the combination of a screw jack comprising two threaded parts, one part constituting a female member adapted to be held in fixed 90 position relative to the concrete construction and the other part constituting a coacting male member threaded into said female member, said male member provided with a rod receiving bore extending axially 95 therethrough and washer mounted loosely on said head at the end thereof opposite the end in threaded engagement in the female member, the outer end of said washer provided with a nut engaging surface and a 100 nut adapted to be threaded on the rod and engaged by said nut engaging surface to withdraw the rod from the concrete when the male member is rotated in one direction. 105

Signed at New York city, in the county 105 of New York and State of New York this 27th day of November A. D. 1918.

ROBERT SHARP.
